J. S. MacKENZIE

INCUBATOR

Filed Oct. 26, 1922.

Inventor
John S. Mackenzie

C. C. Shephard

Attorney

UNITED STATES PATENT OFFICE.

JOHN S. MACKENZIE, OF DELAWARE, OHIO.

INCUBATOR.

Application filed October 26, 1922. Serial No. 596,978.

To all whom it may concern:

Be it known that I, JOHN S. MACKENZIE, a citizen of the United States, residing at Delaware, in the county of Delaware and 5 State of Ohio, have invented certain new and useful Improvements in Incubators, of which the following is a specification.

The present invention is directed to improvements in incubators.

10 The primary object of the invention is to provide an incubator having a cooling compartment between the incubation chambers, said compartment being so arranged that the egg trays can be removed from the incubation chambers at certain intervals and placed in the cooling compartment for a predetermined period to aid in the process of incubation. It is a well known fact that during the process of incubation it is necessary to cool the eggs at intervals, and heretofore it was necessary after removing the egg containing trays from the respective incubation chambers to place them on tables or the like, which not only consumed time 20 but was extremely inconvenient, and owing to the unnecessary handling detrimental, and it is to overcome these objections that the present invention has been perfected.

With these and other objects in view, as 30 will appear as the description proceeds, the invention consists in the novel features of construction, combinations of elements and arrangements of parts, and hereinafter to be fully described and pointed out in the 35 appended claims.

In the accompanying drawing:

Figure 1 is a front view of the incubator, and

40 Figure 2 is a sectional view on the line 2-2 of Figure 1.

Referring to the drawing, 1 designates the incubator which consists of upper and lower incubation chambers 2 and 3, respectively, said chambers being held rigidly 45 spaced in vertical relationship by end sections 4, said sections having their lower ends provided with legs 5 which serve to support the incubator. By this construction a compartment 6 is provided between 50 the chambers 2 and 3, the ends 4 constituting closures for the ends of said compart-

ment, while both sides of said compartment are open. This compartment has located therein a plurality of vertical posts 7 which are disposed adjacent the open sides of the 55 compartment and have their upper and lower ends fixed to the chambers 2 and 3 respectively. These posts serve to support the transverse partitions 8 and floor 9, the latter dividing the compartment into upper 60 and lower tray receiving chambers 10 and 11 respectively. It will be observed that the partitions 8 are of such height as to not contact with the bottom and top of the chambers 2 and 3, thereby providing space to 65 permit the free circulation of air.

The partitions 8 have fixed on their opposite sides tray guides 12, similar guides 13 being associated with the inner face of the ends 4, said guides serving to slidably receive the egg trays 14 when removed from their respective chambers 2 and 3.

It will be apparent that the trays 12 when removed from the incubation chamber 2 will be placed in the upper chamber 10, while the 75 trays from the chamber 3 will be placed in the chamber 11 when it is desired to cool the eggs in said trays.

The chambers 2 and 3 have associated therewith independent heating units 15 of 80 any well known construction and it will be further observed that by providing the compartment 6 that heat from the lower chamber 3 will be prevented from heating the chamber 2, as would occur should the 85 chambers be in mutual contact.

It is a well known fact that certain fumes arise from incubation chambers and in the present instance the floor 9 will serve to prevent any fumes rising from the lower 90 incubation chamber to the upper incubation chamber, or in other words said floor serves as a baffle or deflector.

What is claimed is:

1. An incubator comprising upper and lower incubation chambers, said chambers being vertically spaced to provide tray receiving chambers.
2. An incubator comprising upper and lower incubation chambers for containing egg trays, said chambers being vertically spaced to provide upper and lower tray re-

ceiving chambers for receiving the egg trays when removed from their respective incubation chambers.

3. An incubator comprising upper and lower incubation chambers for containing egg trays, said chambers being vertically spaced to provide an open sided compartment, transverse partitions mounted in the compartment, a floor dividing the compartment into upper and lower tray receiving chambers for slidably receiving the egg trays from the respective incubation chambers.

In testimony whereof I affix my signature.

JOHN S. MACKENZIE.
